Primary Examiner — Stacia Cadmus(74) *Attorney, Agent, or Firm* — Laurence A. Greenberg; Werner H. Stemmer; Ralph E. Locher(57) **CLAIM**

The ornamental design for a tire tread for a vehicle tire, as shown and described.

DESCRIPTION

FIG. 1 is a perspective view of a tire tread for a vehicle tire, showing my new design;

FIG. 2 is a front elevational view thereof;

FIG. 3 is an enlarged partial front view thereof;

FIG. 4 is a right side elevational view thereof; and,

FIG. 5 is a left side elevational view thereof.

The dash-dot lines showing the boundaries of the illustrated detail form no part of the claimed design. The broken line showing of the inner bead depicts environmental subject matter that forms no part of the claimed design. While only portions of the tread design are shown, it should be understood that the tread covers the tire circumferentially in its entirety.
